UNITED STATES PATENT OFFICE.

WILLIAM SPALCKHAVER, OF NEW YORK, N. Y., ASSIGNOR, BY MESNE ASSIGNMENTS,
TO R. HOE AND CO., OF NEW YORK, N. Y., A CORPORATION OF NEW YORK.

DELIVERY MECHANISM FOR PRINTING-MACHINES.

1,122,547.

Specification of Letters Patent.

Patented Dec. 29, 1914.

Application filed June 12, 1908. Serial No. 438,010.

To all whom it may concern:

Be it known that I, WILLIAM SPALCKHAVER, a citizen of the United States, residing at New York, county of Kings, and 5 State of New York, have invented certain new and useful Improvements in Delivery Mechanism for Printing-Machines, fully described and represented in the following specification and the accompanying drawings, forming a part of the same.

This invention relates to certain improvements in delivery mechanism for printing machines.

In producing certain folded products on a 15 printing machine, it is desirable, under some circumstances, to have the folded edge of the product sharply defined, as, for instance, where the printing machine is to produce signatures which are to be afterward put 20 into a collating machine to be assembled for binding.

The present invention has for its object to produce a delivery mechanism for printing machines delivering a folded product by 25 which the folded edge of the product is sharply defined.

With this and other objects in view, the invention consists in certain constructions and in certain parts, improvements and combinations, as will be hereinafter fully described and then specifically pointed out.

Referring to the accompanying drawings—Figure 1 is a diagrammatic sectional side elevation of so much of a delivery mechanism of a printing machine as is necessary to an understanding of the invention. Fig. 2 is an end elevation of the construction illustrated in Fig. 1.

Referring to said drawings, which illustrate one embodiment of the invention, 1 represents a tucking cylinder of ordinary type from which the sheets are delivered by means of a tucking blade, indicated at 2 in dotted lines, to a pair of tucking jaws 3, 45 these jaws being mounted on an ordinary folding cylinder 4. The type of folding mechanism just described is well-known in the art, and a specific description of its action is unnecessary. The folded sheets are delivered from the cylinder 4 to a forwarding or 50 delivery cylinder 5 mounted on the shaft 6, the folded edge of the sheets being taken, in the construction illustrated, by grippers 7 operated in the usual manner, by means of a 55 lever 8, cam 9, and spring rod 10. It has

been found in practice, particularly where the product being handled is either a thick product or consists of a good quality of heavy paper, or both, that the fold produced by the folding mechanism is not sufficiently defined for certain purposes, as, for instance, where the signatures are to be operated upon by a collating machine. Means are, therefore, provided for sharpening and defining the fold. While these means may be varied 60 widely in construction, in the particular machine illustrated, they include an abutment 11 which underlies the sheet at its folded edge. Suitable coöperating pressing devices which may be varied in construction will be 65 used in connection with this abutment when the abutment is employed. In the particular construction illustrated, these coöperating pressing devices consist of two sets of rolls 12, 13, so arranged that the edge of the 70 sheet is presented to them in succession. In the best constructions and as shown, the rolls of each set will be spaced apart so as to straddle the gripper fingers 7 as they pass them. If desired, these rolls 12 and 13 may 75 be driven. In the construction illustrated, the rolls 12 are mounted on a shaft 14 and the rolls 13 are mounted on a shaft 15. The shaft 14 is shown as provided with a gear 16 which is in mesh with a gear 17 mounted 80 on the cylinder shaft 6 and the shaft 15 is provided with a similar gear 18 which is 85 also in mesh with the gear 17.

In the best constructions, the pressing devices will be made adjustable, so that the 90 pressing effect may be exactly defined. In the particular machine illustrated, the shaft 14 is mounted in hangers 19, depending from an angle or brace-bar 20 supported in the side frames of the machine. The 95 hangers 19 are secured to the bar 20 by means of bolts 21, or in any other suitable manner, the hangers being slotted so as to make the shaft and rolls adjustable vertically. If desired, stop screws 22 provided 100 with lock nuts 23 may be employed to prevent any shifting of the rolls. Similarly, the shaft 15 is supported in hangers 24 secured to the brace-bar by means of bolts 25, stop screws 26 being employed in connection 105 therewith.

The particular machine shown is provided with a slitting mechanism of usual type, the slitter being marked 27. It is mounted on a shaft 28 driven by a gear 29 meshing with a 110

gear 30 on the shaft 6. The shaft 6 may be driven in any suitable manner, as by a gear 31 which meshes with any suitable driving gear. The sheets may be delivered from the 5 forwarding cylinder in any suitable manner. As shown, the pressed sheets are stripped from the cylinder by means of strippers 32 and fall into receiving compartments in a chain receiver 33 of usual construction.

10 Changes and variations may be made in the construction by which the invention is carried into effect. The invention is not, therefore, to be limited to the particular construction above described and illustrated in 15 the accompanying drawings.

What is claimed is:—

1. In a delivery mechanism, the combination with means for folding a sheet, of a cylinder to which the folded sheet is delivered, said cylinder having means for forwarding the sheet, and means for pressing a substantial portion of the folded edge of the sheet while on the cylinder whereby the fold is sharpened.

25 2. In a delivery mechanism, the combination with means for folding a sheet, of a cylinder to which the folded sheet is delivered, a pressure abutment on the cylinder arranged to underlie the sheet at its 30 folded edge, and means coöperating with the abutment to press a substantial portion of the folded edge of the sheet and sharpen the fold.

3. In a delivery mechanism, the combination with means for folding a sheet, of a cylinder to which the folded sheet is delivered, said cylinder having means for forwarding the sheet, and a roll-pressure mechanism coöperating with the cylinder to 40 press a substantial portion of and thereby to sharpen the folded edge of the sheet.

4. In a delivery mechanism, the combination with means for folding a sheet, of a forwarding cylinder having grippers operating on the folded edge of the sheet, and means operating on a substantial portion of the folded edge of the sheet between the grippers whereby the fold is sharpened.

5. In a delivery mechanism, the combination with means for folding a sheet, of a forwarding cylinder having grippers operating on a substantial portion of the folded edge of the sheet, and a plurality of rolls operating on the folded edge of the sheet

between the grippers whereby the fold is 55 sharpened.

6. In a delivery mechanism, the combination with means for folding a sheet, of a forwarding cylinder having grippers operating on the folded edge of the sheet, 60 and a plurality of adjustable rolls operating on the folded edge of the sheet between the grippers to sharpen the fold.

7. In a delivery mechanism, the combination with means for folding a sheet, of a 65 forwarding cylinder having grippers operating on the folded edge of the sheet, an abutment underlying the sheet near its folded edge, and a plurality of adjustable rolls operating on the folded edge of the 70 sheet between the grippers to sharpen the fold.

8. In a delivery mechanism, the combination with means for folding a sheet, of a forwarding cylinder having grippers operating on the folded edge of the sheet, 75 and a plurality of sets of pressure rolls to which the sheets are presented in succession, the rolls operating on the folded edge of the sheet between the grippers to sharpen 80 the fold.

9. In a delivery mechanism, the combination with means for folding a sheet, of a forwarding cylinder having grippers operating on the folded edge of the sheet, 85 and a plurality of sets of adjustable pressure rolls to which the sheets are presented in succession, the rolls operating on the folded edge of the sheet between the grippers to sharpen 90 the fold.

10. In a delivery mechanism, the combination with means for folding a sheet, of a forwarding cylinder having grippers for operating on the folded edge of the sheet, an abutment underlying the sheet near its 95 folded edge, and a plurality of sets of adjustable rolls to which the folded edge of the sheet is presented in succession, the rolls operating on the folded edge of the sheet between the grippers to sharpen the fold. 100

In testimony whereof, I have hereunto set my hand, in the presence of two subscribing witnesses.

WILLIAM SPALCKHAVER.
